UNITED STATES PATENT OFFICE.

MORGAN K. ARMSTRONG, OF CHICAGO, ILLINOIS, ASSIGNOR TO BESTWALL MANUFACTURING COMPANY, OF CHICAGO, ILLINOIS, A CORPORATION OF DELAWARE.

WEATHER-BOARD.

1,322,278.

Specification of Letters Patent.

Patented Nov. 18, 1919.

Application filed February 20, 1915. Serial No. 9,525.

To all whom it may concern:

Be it known that I, MORGAN K. ARMSTRONG, a citizen of the United States, and a resident of Chicago, in the county of Cook 5 and State of Illinois, have invented certain new and useful Improvements in Weather-Board; and I do hereby declare that the following is a full, clear, and exact description thereof, reference being had to the accompanying drawings, and to the letters 10 of reference marked thereon, which form a part of this specification.

This invention relates to improvements in weather board for roofing, siding and 15 like purposes, and consists of the matters hereinafter described and more particularly pointed out in the appended claims.

The object of the invention is to provide 20 a board for roofing or siding of the kind described which shall be economical to manufacture and at the same time shall be of a high grade and efficient for the purpose intended and shall in addition, have such inherent strength in its own body as a board 25 that it will not require the additional support now generally necessary with the composite waterproof roofing and siding that is now on the market.

The various advantages of my invention 30 will appear more fully as I proceed with my specification.

In the drawings:

Figure 1 illustrates a fragmentary top plan view of one form of composite roofing 35 made in accordance with my invention.

Fig. 1^a illustrates a vertical sectional view of said roofing.

Fig. 2 illustrates a fragmentary top plan view of a modified form of my composite 40 roofing.

Fig. 2^a illustrates a vertical section through the same.

Fig. 3 illustrates a fragmentary top plan view of another form of composite roofing 45 embodied in my invention.

Fig. 3^a illustrates a vertical section through that form of roofing shown in Fig. 3.

Fig. 4 illustrates a fragmentary top plan 50 view of a further modified form of my improved composite roofing.

Fig. 4^a illustrates a vertical section through the same.

Fig. 5 illustrates a fragmentary top plan view of a still further modified form of 55 composite roofing made in accordance with my invention, and

Fig. 5^a illustrates a vertical section there- 60 through.

My improved weather board is built upon 60 a plaster board as its base, the same consisting of top and bottom layers of fibrous material such as paper and of an intermediate layer of plastic composition. The weather board is treated with a waterproof- 65 ing material, preferably an asphaltum, and a layer or covering of crushed stone, crushed tiling or like is applied to one surface of the board so treated to protect not only the plaster board but also the waterproofing ma- 70 terial from damage caused in various ways. Instead of the crushed stone or tiling before referred to, a protective covering consisting of a sheet of waterproof paper such as felt paper may be used, said protective coverings 75 all adhering to the waterproof material used. The water proofing material may be applied to the plaster board, by immersing it in a bath of liquid asphaltum until thoroughly impregnated therewith, in which 80 case the stiffness of the board is increased without making it brittle. The waterproofing material may be so applied to the board as not to impregnate it, but only to provide a coating of such material either on one or 85 both surfaces thereof, whichever is desirable.

Referring now to the accompanying drawings, and more particularly to Figs. 1 and 1^a, 10 indicates a plaster board which 90 forms the base of my improved weather board. The said plaster board base 10 as heretofore stated consists of top and bottom layers 12, 13, of fibrous material such as paper and of an intermediate layer 11 of 95 plastic composition. The said plaster board is a product which may be obtained on the market and is of sufficient thickness and weight to provide the required and necessary rigidity and strength for the weather 100 board.

In manufacturing the roofing illustrated

in Fig. 1, the base 10 is treated with asphaltum in a liquid state. The plastic composition being porous, and its protective coverings being fibrous, said base 10 will absorb 5 asphaltum until permeated therewith.

While still wet, fine particles of crushed rock 14 are sprinkled over the top surface of the fibrous protective covering 12. The crushed rock so applied is spread evenly 10 over the surface and pressed thereinto by a suitable pressure device and the whole left to dry. Such excess asphaltum (indicated at 16 in Fig. 1) as will remain on the exposed face of the covering 12 will act as a 15 binder and cause the particles of rock to adhere to the surface to which they are applied. The base 10 when so treated becomes stiff and rigid but not brittle. This is the preferable and most economical way to prepare 20 the weather board, wherein the plaster board is permeated with asphaltum. Should the plaster board, however, be allowed to dry before the protective covering of rock is applied, it will be necessary to apply an 25 additional coating of asphaltum to the top surface of the plaster board when providing the same with such an outer protective covering.

In Figs. 2 and 2^a is illustrated a modified 30 form of weather board and in said figures 10^a indicates the plaster board, 12^a, 13^a respectively, the top and bottom fibrous coverings of said board, and 11^a the plastic layer between said fibrous coverings. To the top 35 surface of the fibrous protective covering 12^a is applied a layer or coating of asphaltum, 16^a, of the consistency of coal tar, which will adhere to the said covering. Over this layer of asphaltum is applied a 40 covering of tile dust 17 which is evenly spread over the surface of the asphaltum and suitable pressure applied thereto so as to partly embed the tile particles within the asphalt. One of the advantages attained in 45 using tile in this form is that different colors of roofing may be had and at the same time, a substance which has heretofore been wasted is made use of.

In Figs. 3 and 3^a is shown another modified 50 form of weather board in which the waterproof layer 16^b of asphaltum is provided with a protective covering consisting of a sheet of felt paper 18, or like waterproofed fibrous material. The felt paper is, 55 during the manufacture thereof, impregnated with a liquid asphaltum and provided with a sprinkling of mica upon its exposed surface. The paper 18 being analogous with respect to the asphaltum will readily and 60 tenaciously adhere thereto after having been applied by pressure.

In Figs. 4 and 4^a are shown parts of the plaster board in which the outer protective covering consists of crushed stone. 19 indi-

cates the layer of crushed stone and 16^c the 65 waterproofing asphaltum. The crushed rock in this instance is applied to and evenly spread over the layer of asphaltum 16^c and is pressed into the surface thereof by means of a suitable pressure device. That part of 70 the crushed rock particles embedded in the asphaltum will be caused to adhere thereto and that part of the crushed rock particles above the surface will lie in close formation with respect to each other and assist in the 75 effectual shedding of water. The same pressure which is used in embedding the crushed rock in the asphaltum will force the asphaltum into the interstices of the top protective covering of fibrous material 12^c. 80

In Figs. 5 and 5^a is shown a weather board which is quite similar to that shown in Figs. 4 and 4^a with the exception that in addition to the waterproof covering on the top side of the board there is provided a similar 85 layer of waterproof material 20 on the bottom side of board. This layer is preferably of asphaltum. The top of the board is covered with a protective covering of crushed rock 19^d adhering to the top layer of asphaltum 16^d as before. Manifestly any of 90 the protective coverings as described in the other cases may be used in the construction illustrated in Figs. 5 and 5^a. The additional layer of waterproofing material on the bottom 95 of the board adds to its weight and also increases its efficiency as a weather board.

The weather board made as described herein will be rigid and strong so as not to require the support of an undersheathing as 100 in the case of ordinary roofing. In addition, the coefficient of expansion of the board will be very small so that it is not liable to crack under the action of the elements. It is sufficiently rigid so that it will 105 not buckle and roofing or siding made from the improved weather board will always lie substantially in a plane. The improved weather board is substantially fire-proof 110 since the materials from which it is made are not inflammable. The most damage that would be done to such weather board where sparks or hot coals fall upon it would be to melt the asphaltum in the neighborhood of 115 where the spark fell.

The weather board, as will be manifest, may be made and supplied in flat sheets and may be laid and applied in the same way as ordinary planking. The outer covering may be colored by the use of rock of different 120 colors so that the tone of the roofing may be made to harmonize with the color of the building to which it is applied.

I claim as my invention:

A weather board for roofing, siding and 125 the like, comprising a base consisting of an intermediate porous plaster body and top and bottom coverings of paper adhered to

said plaster body, said base being soaked in asphaltum, and a protective covering of crushed stone for said top paper covering of said base, adhering thereto through the 5 agency of the said asphaltum.

In testimony, that I claim the foregoing as my invention I affix my signature in the

presence of two witnesses, this 11th day of February, A. D. 1915.

MORGAN K. ARMSTRONG.
